LIGHT SHADE

Robert A. Hanlin, Logansport, Ind., assignor to H & H Products, Inc., Logansport, Ind., a corporation of Indiana

Application April 25, 1955, Serial No. 503,523

6 Claims. (Cl. 240—47)

This invention relates in general to new and useful improvements in electric lights, and more specifically to an improved shade construction for electric lights.

The average electric bulb is of the incandescent type. Therefore, when the bulb burns, in order to emit light, there is also produced a relatively large quantity of heat. Due to this heat being emitted by the light bulb, any shade, particularly a metal shade, surrounding the light bulb will have heat transmitted thereto. Inasmuch as people often come into contact with the shade, it is very desirable that the shade be relatively cool to the touch in order to prevent both injury and momentary fright.

It is therefore the primary object of this invention to provide an improved light shade construction which is so insulated and so ventilated whereby the part of the light shade construction exposed to the touch remains relatively cool although the light bulb disposed therein has been burning for a long period of time and emitting a large amount of heat.

Still another object of this invention is to provide an improved light shade construction which includes an outer metal shade and inner shade formed of insulating material, the insulating material being provided with a suitable coating to deflect both light and heat whereby a maximum amount of light is deflected from the light shade, and at the same time, a minimum amount of heat is transmitted to an outer shade.

A further object of this invention is to provide an improved inner shade for use in conjunction with metal shades of generally conventional types, the inner shade being so constructed whereby it may be supported by a bulb socket of the light construction and centered with respect to the outer shade.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of an electric light incorporating the light shade assembly which is the subject of this invention;

Figure 2 is a perspective view of the inner insulated shade which is a primary element of the present invention;

Figure 3 is a vertical sectional view taken substantially on the plane indicated by the section line 3—3 of Figure 1 and shows the specific relationship between the various parts of the shade assembly; and

Figure 4 is a transverse sectional view taken substantially upon the plane indicated by the section line 4—4 of Figure 3 and shows the manner in which the inner shade is centered with respect to the outer shade.

Referring now to the drawings in detail, it will be seen that there is illustrated an electric light construction which is referred to in general by the reference

2

numeral 10. The electric light construction 10 includes an outer shade, which is referred to in general by the reference numeral 12, and inner shade, which is referred to in general by the reference numeral 14.

The outer shade 12 includes a lower truncated conical portion 16 which has connected thereto by an annular flange portion 18 an upper cylindrical portion 20. The cylindrical portion 20 terminates in a top wall 22.

Suspended from the top wall 22 is a light bulb socket 24. The light bulb socket 24 is maintained in position with respect to the top wall 22 by a split structure 26.

The outer shade 12 is supported by a flexible conduit 28. The conduit 28 is removably connected to the outer shade 12 by means of a fitting 30. Extending through the conduit 28, which also functions as a support, is a pair of electrical conductors 32. The electrical conductors 32 are connected to the switch assembly 26 and to the light bulb socket 24.

Disposed in the light bulb socket 24 is an upper portion of a conventional electric bulb 34 of the incandescent type. When the electric bulb 34 burns, a great amount of heat emits therefrom and is transmitted to the outer shade 12. Inasmuch as the outer shade 12 is normally formed of metal, it becomes overheated and quite hot to the touch.

In order to overcome the heating of the outer shade 12, there is mounted within the outer shade 12 the inner shade 14.

The inner shade 14 includes a truncated conical lower portion 36 which is connected to a generally cylindrical upper portion 38. The upper portion 38 terminates in a top wall 40 having a central opening 42 therethrough. Disposed at the lower edge of the lower portion 36 is a plurality of circumferentially spaced, radiating tabs 44.

Referring now to Figure 3 in particular, it will be seen that when the inner shade 14 is positioned within the outer shade 12, the cylindrical portion 38 is telescoped over the light bulb socket 24 and the top wall 40 rests upon the upper end of the light bulb socket 24. Also, the switch assembly 26 passes through the opening 42 in the top wall 40. The lower portion of the inner shade 14 is centered with respect to the outer shade 12 by the tabs 44, the tabs 44 being of a size to engage the inner surface of the outer shade 12.

In order that a maximum amount of light may be reflected from the inner shade 14 and at the same time, a maximum amount of heat may be reflected away from the outer shade 12, the inner surface of the inner shade 14 is provided with a coating of light and heat reflecting material. This material is preferably in the form of either an aluminized coating or a lacquered coating.

The cylindrical portion 20 of the outer shade 12 is provided with a plurality of vertically extending, circumferentially spaced louvers 46. The louvers 46 permit the escape of air which has become heated while being disposed between the outer shade 12 and the inner shade 14. Inasmuch as the lower end of the inner shade 14 is spaced from the outer shade 12 with the exception of the tabs 44, it will be readily apparent that air will be permitted to pass up into the space between the outer shade 12 and the inner shade 14. Since the air disposed between the two shades 12 and 14 will become heated, it will rise and pass through the louvers 46. This process is continuously repeated, and thereby forming an air cooling pocket between the shades 12 and 14. This, coupled with the reflective coating on the inner surface of the inner shade 14, and the forming of the inner shade 14 of a suitable insulating material, such as asbestos, results in the cooling of the outer shade 12 to a maximum.

The foregoing is considered as illustrative only of

the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A light shade construction comprising an outer shade, a socket suspended from said outer shade, means for keeping said outer shade cool, said means including an inner shade suspended from said socket in spaced telescoped relation to said outer shade to form a ventilated air space, said inner shade being formed of a heat insulating material whereby heat transfer to said outer shade is retarded.

2. A light shade construction comprising an outer shade, a socket suspended from said outer shade, means for keeping said outer shade cool, said means including an inner shade suspended from said socket in spaced telescoped relation to said outer shade to form a ventilated air space, said inner shade having radiating tabs at a lower end thereof, said tabs engaging said outer shade and centering said inner shade, said inner shade being formed of a heat insulating material whereby heat transfer to said outer shade is retarded.

3. A light shade construction comprising an outer truncated conical shade having a top wall, a socket suspended from said top wall, means for keeping said outer shade cool, said means including an inner truncated conical shade suspended from said socket in spaced telescoped relation to said outer shade to form a ventilated air space, said inner and outer shades having tapers of different angles whereby the spacing between said shades increases towards said top wall.

4. A light shade construction comprising an outer truncated conical shade having a top wall, a socket suspended from said top wall, means for keeping said outer shade cool, said means including an inner truncated conical shade suspended from said socket in spaced telescoped relation to said outer shade to form a ventilated air space, said inner and outer shades having tapers of different angles whereby the spacing between said shades increases towards said top wall, said inner

shade having radiating tabs at a lower end thereof, said tabs frictionally engaging said outer shade and centering said inner shade.

5. A light shade construction comprising an outer truncated conical shade having a top wall, a socket suspended from said top wall, means for keeping said outer shade cool, said means including an inner truncated conical shade suspended from said socket in spaced telescoped relation to said outer shade to form a ventilated air space, said inner and outer shades having tapers of different angles whereby the spacing between said shades increases towards said top wall, said inner shade being formed of a heat insulating material whereby heat transfer to said outer shade is retarded.

6. A light shade construction comprising an outer truncated conical shade having a top wall, a socket suspended from said top wall, means for keeping said outer shade cool, said means including an inner truncated conical shade suspended from said socket in spaced telescoped relation to said outer shade to form a ventilated air space, said inner and outer shades having tapers of different angles whereby the spacing between said shades increases towards said top wall, said inner shade having radiating tabs at a lower end thereof, said tabs frictionally engaging said outer shade and centering said inner shade, said inner shade being formed of a heat insulating material whereby heat transfer to said outer shade is retarded.
